CLAIM

The ornamental design for a lamp with adjustable focus and color temperature as shown and described.

DESCRIPTION

FIG. 1 is a perspective view of a lamp with adjustable focus and color temperature showing my design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof; and,

FIG. 8 is a bottom perspective view of the lamp with adjustable focus and color temperature.

The broken lines shown in the drawings depict portions of the lamp that form no part of the claimed design.

1 Claim, 7 Drawing Sheets
